UNITED STATES PATENT OFFICE

HARRY H. BARBER, OF AURORA, ILLINOIS, ASSIGNOR TO BARBER-GREENE COMPANY,
OF AURORA, ILLINOIS, A CORPORATION OF ILLINOIS

SCRAPER FOR DITCHING MACHINES

Application filed August 21, 1928. Serial No. 301,026.

This invention relates to a scraper for ditching machines.

It is an object of this invention to provide a scraper which can be elevated for passing over pipes or obstructions, and which can readily be removed from its operative position in cases where it is desired to dig straight down at a curbing or sidewalk, or when it is desired to dig post holes.

10 It is a further object of this invention to provide a scraper construction which can be adjusted into more compact form and supported adjacent the frame of the machine when it is desired to remove the said scraper 15 when post holes or the like are dug.

It is also an object of this invention to employ safety means that will give or fracture when the scraper encounters an overload or obstruction.

20 The invention comprises the novel structure and combination of parts hereinafter described and more particularly pointed out and defined in the appended claims.

In the accompanying drawings which illustrate a preferred form of this invention, and in which similar reference numerals refer to similar features in the different views.

Figure 1 is a fragmentary side elevational view of ditching machine equipped with a 30 scraper involving this invention.

Figure 2 is an enlarged elevational view of the scraper and the structure above said scraper illustrating in dotted lines its removed position.

35 Figure 3 is a fragmentary top plan view of the mechanism shown in Figure 2.

Figure 4 is a reduced fragmentary elevational view upon the line IV—IV of Figure 2 looking in the direction of the arrows.

40 Figure 5 is an enlarged front elevational view of the scraper.

Figure 6 is a sectional view upon the line VI—VI of Figure 5.

45 Figure 7 is an enlarged sectional view upon the line VII—VII of Figure 4.

Figure 8 is a sectional view upon the line VIII—VIII of Figure 2.

50 Figure 9 is a fragmentary plan view illustrating the locking plate for the connecting

rod of the telescopic sections of a part of the scraper support.

In the drawings, certain parts of a ditching machine have been illustrated in order that the relation of the present invention thereto may be more readily understood. The numeral 1 represents a vertical boom that is supported upon a crawler by the radius rods 2. The boom 1 carries a frame for supporting the cross conveyor. The particular structure of this frame is immaterial from the standpoint of this invention, and only certain elements thereof need be mentioned. These elements are the transverse parallel beams or bars 3, only one of which is shown, 65 and the upright elements 4.

The frame elements 3 suspend a support for a scraper, and this support is shown as of triangular form consisting of the vertical legs 5 which are pivoted to gusset plates 6 70 secured to one end of the frame elements 3, and diagonal legs 7 which are removably secured to the other ends of the frame elements 3 in a manner that will now be set forth. A gusset plate 8 (Figure 8), is provided with 75 attaching flanges 9 which are secured to the elements 3, which gusset plate 8 is reinforced by a channel or angular section 10. A channel section 11 is secured to the gusset plate 8 by means of two frangible pins or bolts 11a. 80 The upper ends of the legs 7 of the scraper support are spanned by a channel member 12 to which angle clips 13 are secured, and which angle clips are adapted for removable attachment to the flanges of channel 11 by a 85 frangible bolt 39 as shown in Figure 8. The channel section 12 is preferably connected to the legs 7 by means of small angular pieces 14 which are secured by bolts or rivets 15.

The legs 5 of the scraper support are made 90 of telescopic sections 5a and 5b. The section members 5a are in the form of angle bars to which a separator bar 16 is secured. The lower section members 5b are in the form 95 of strips which overlap the upper section members, and are suspended therefrom by a removable locking bolt 17 having a handle 18 extending at right angles thereto.

Mechanism has been provided for maintaining the telescopic sections 5a and 5b in 100

substantial alignment. To this end, a terminally flanged strip 19 is attached to the section members 5a by angle clips 20. The terminal flanges 19a thereof overlap the sections 5b and confine the same against the flanges of the angle members 5a that are parallel thereto as shown in Figure 7. A stop member 21 is secured to one of the section members 5a above the strip 19 with which it is adapted to abut when the parts are in operative position as shown in full lines in the drawings. Upon the other section member 5a there is secured a locking plate 22 which has an upwardly directed narrow portion 15 or projection 23 (Figure 9) that overlaps the handle 18 of the locking bolt 17 with the result that the handle 18 must first be rotated from under said extension before the bolt can be withdrawn.

20 The lower ends of the legs 7 are pivoted to the lower ends of the legs 5 as indicated at 24. The legs 7 carry the scraper 25 which is adapted to travel behind the digging boom for cleaning up the dug trench. This scraper 25 is slidably mounted upon the legs 7 of the scraper support as will now be set forth.

Extending along the margins of the front face of the scraper are metal strips 25a which are attached to the scraper. Suitable guides 30 26 are carried by these strips for receiving the legs 7 as shown in Figures 5 and 6. The back of the scraper is reinforced by angle strips 28 and flexible sweep strips 29 of rubber or the like are attached in superposed 35 relation upon the attaching flanges of the reinforcing angles 28, by bolts 27 which extend through the strips 25a and secure the reinforcing angles, which are also secured by the securing bolts of the strips 25a. The upward 40 and downward sliding movements of the scraper are limited by stops 7a upon the legs 7. The upper guides engage these stops upon downward movement while the lower guides engage said stops upon upward movement.

45 The scraper 25 may be elevated upon the legs 7 by means of a cable 30 attached thereto. This cable extends to the top of the frame where it is trained around a drum 31 and fastened thereto. The drum 31 is secured to a shaft 32 journalled in suitable 50 bearings upon the frame. A gear 33 secured upon the shaft 32 is driven by a small gear 34 secured upon a shaft 35 journalled in the bearings upon the frame. A pulley 36 is secured upon the shaft 35 and an endless cable 37 is trained over this pulley. The cable 37 is adapted to be manually operated 55 for rotating the shaft 35 and winding the cable 30 upon the drum 31 when the scraper or the scraper support is elevated. The cable 60 37 which is in the form of a chain is adapted to be attached to a hook 40 (Figure 1) or the like to anchor the same against movement.

65 The aforementioned angle clips 13 on the

bridge piece 12 extend above the top of the legs 7 and a safety cable 38 connects the angle extensions with the frame, so that the scraper may be supported thereby when the frangible connections break.

70 In use, the scraper normally occupies the position shown in full lines in the drawings. Now if an obstruction such as a service pipe should be encountered, the cable 37 may be operated for elevating the scraper upon its 75 support.

The scraper and its support may also be elevated into the dotted line position shown in Figure 2, in the following manner:

75 The scraper is elevated by winding the cable 30 upon its drum by pulling upon the cable 37 until the lower guides of the scraper strike the stops 7a. The connecting pins 17 and 39 are then removed and the safety cable 38 is unhooked from the scraper support. 80 The hoisting operation effected by pulling upon the cable 37 is then continued with the result that the leg sections 5b will slide upward upon the sections 5a until the former are in complete telescopic relation with the 85 latter. The two sections in such telescopic relation will then swing upon the pivots of the upper sections 5a into a horizontal plane beneath the frame members 3 as shown in dotted lines in Figure 2, and the legs 7 carrying the scraper will be elevated in vertical 90 position against the outer vertical face of the frame as shown in dotted lines. In this position the cooperating chain 37 may be attached to the hook 40 to maintain the parts 95 in elevated position. A reverse operation will bring the parts to their operative position. 100

If, during the use of the ditching machine, an obstruction of sufficient magnitude should be encountered by the scraper, the frangible pin 39 would be broken and the scraper would be supported by the safety chain 38. If the strength of the frangible bolt 39 should exceed that of the frangible bolts 11a, the latter would be the first to break upon over-load. However, it is more desirable to use a frangible bolt 39 that is weaker than the combined frangible bolts 11a since the frangible bolt 39 may be more readily replaced. 110

115 From the foregoing, it will be apparent that a very simple support and hoisting mechanism for a scraper has been provided which allows the scraper to be elevated for passing over an obstruction and which allows the scraper and its support to be elevated when it is desired to dig post holes, or when it is desired to dig adjacent a curbing or sidewalk.

120 I am aware that many changes may be made, and numerous details of construction may be varied through a wide range without departing from the principles of this invention, and, I therefore, do not purpose limiting the patent granted hereon, otherwise than necessitated by the prior art. 125

I claim as my invention:

1. In a ditching machine embodying a frame, a scraper support mounted upon said frame for upward swinging movements, a scraper slidably supported upon said support, and means for controlling the sliding movements of said scraper.
  2. In a ditching machine embodying a frame, a scraper support comprising a member pivoted to said frame and a member removably secured to said frame, a scraper slidably mounted upon said support, said first mentioned member being telescopic, and hoisting mechanism for elevating said scraper and said support against said frame.
  3. In a ditching machine embodying a frame, a scraper support upon said frame, said support comprising a pair of slidably adjustably pendant members pivoted to said frame, and a pendant member removably secured to said frame, a scraper slidably mounted upon said support, and hoisting mechanism for elevating said scraper, slidably adjusting said pair of members and 25 swinging the same into horizontal position and elevating the other member.
  4. In a ditching machine embodying a frame, a scraper support comprising a member pivotally secured to said frame and a member removably secured to said frame, and hoisting mechanism for swinging said support upon the pivotal connection of the first member when the removably secured member is released.
  5. In a ditching machine, a supporting frame member, a depending member pivoted to said frame member, a second depending member pivoted at its lower end to said first member and removably secured to said frame member, and a scraper on said second member, hoisting mechanism for swinging said first member upon its pivot when the second member is released from the frame member.
  6. In a ditching machine embodying frame members, a scraper support having pivotal connection with said frame members, and removable connection with said frame members, and hoisting mechanism for swinging said support upon its pivotal connection when 50 said removable connection is removed.
  7. In a ditching machine, a frame member, a scraper support comprising a contractile member pivoted to said frame member, and a member removably secured to said frame member, a scraper slidably attached to said second member, and hoisting mechanism for elevating said scraper, contracting said first member and elevating said support when said second mentioned member is released from said frame member.
  8. In a ditching machine embodying a frame member, a contractable scraper support depending from said frame, a scraper slidably mounted upon said support, and 65 means for sliding said scraper upon said sup-
  - port, contracting said support and elevating the same.
  9. In a ditching machine embodying a frame member, a scraper support having pivotal connection with said frame member and also a frangible connection therewith, and a safety connection for supporting said scraper support when said frangible connection fails.
  10. In a ditching machine embodying a frame member, a scraper support having a 70 pivotal connection with said frame member, and also a frangible connection therewith, and means for sustaining said support if the frangible connection fails.
  11. In a ditching machine embodying a frame member, a scraper support consisting of a pair of pivotally connected elements, one element being pivotally connected to said frame member and the other element being removably secured thereto whereby the first element may be swung into horizontal position and the other into vertical position when said removably secured element is released.
  12. In a ditching machine embodying a frame member, a scraper support comprising a pair of elements secured to said frame member for forming a rigid support, one of said elements being releasable from said frame member whereby said scraper support may be deformed, and means for elevating 90 and simultaneously deforming said support.
- In testimony whereof, I have hereunto subscribed my name.
